DESIGN FOR A SHOE OR SIMILAR ARTICLE

Joseph Sofransky, New York, N. Y.

Application July 26, 1935, Serial No. 57,811

Term of patent 3½ years

To all whom it may concern:

Be it known that I, Joseph Sofransky, a citizen of the United States, residing in New York, in the county of New York and State of New York, have invented a new, original, and ornamental Design for a Shoe or Similar Article, of which the following is a specification, reference being had to the accompanying drawing, forming part thereof.

I claim:

The ornamental design for a shoe or similar article, as shown.

JOSEPH SOFRANSKY.
